UNITED STATES PATENT OFFICE.

PETER H. JACKSON, OF SAN FRANCISCO, CALIFORNIA.

SUPPORT FOR BEAMS AND GIRDERS.

SPECIFICATION forming part of Letters Patent No. 291,192, dated January 1, 1884.

Application filed October 23, 1883. (No model.)

To all whom it may concern:

Be it known that I, PETER H. JACKSON, of the city and county of San Francisco, and State of California, have invented an Improvement 5 in Supports for Beams and Girders; and I hereby declare the following to be a full, clear, and exact description thereof.

My invention relates to an improved connection and support between girders and 10 beams which meet them at right angles, and at points intermediate between their ends.

It consists of independent wrought-iron plates, which extend across the girder or girders, and also over the end of the beam, above 15 and below, and a wrought-iron clamp or band, which surrounds the end of the beam and the plates, together with bolts, wedges, and check-pieces, all of which will be more fully explained by reference to the accompanying drawings, in which—

Figure 1 is a transverse section of two beams lying side by side, forming a girder, with a beam abutting against one side of one beam and the plates and clamps. Fig. 2 is a trans- 25 verse section of the abutting beam and the plates, showing the side of the girder and a view of the band and the check-pieces. Fig. 3 is a view showing the manner of securing a single top plate. Fig. 4 shows side bolts in 30 place of a surrounding band. Fig. 5 shows the top plate with flanges clasping the end of the abutting beam. Fig. 6 is a side view of same.

In my patent of June 12, 1883, I have shown 35 a beam abutting against a girder and supported by a cast-iron shoe having a socket to receive it, and arms extending over the girder. In my present construction I dispense with the cast-iron shoe with tongues 40 forming a part of it, and make a lighter and adjustable construction.

A A is a girder, of which there may be one, two, or more beams, and B is the abutting beam.

C C are wrought-iron plates, of sufficient 45 thickness and width to withstand the strain. These plates extend across the girder and to a short distance upon the end of the beam, one above and one below. A strong wrought-iron band, D, fits over these plates, and may

be shrunk or wedged upon them, so as to 50 clamp them firmly to the end of the beam. Bolts E pass through the girders, and thus hold them firmly in place. If desired or necessary, wedges or keys F may be driven in between the beam and the plates, so as to give 55 the plates an even bearing and make them firm and rigid. Check-pieces G are fitted to the sides of the beam, and extending flush with the top and bottom of the beam, to which they are bolted, they fill the space at the sides 60 inside the band D. The girders, when two or more are placed side by side, may have the intermediate diaphragms, H, to bind them together and distribute the weight, as shown in my former patent. If the load is light, a single plate, C, may be employed, extending along the top of the beam and girder, being secured by a band, as before described, and having the opposite end bent into a hook, which clasps the top flange of the girder at the opposite side, as shown in Fig. 3. In some cases the band D may be dispensed with and its place supplied by the bolts I, which pass through the plates C at each side of the beam B, and also through or at the side of the check-pieces G, as in Fig. 4.

Fig. 5 shows the top plate, C, extending across the girder, as before described, and having that portion which extends above the abutting beam B provided with flanges c c, which 80 are folded over the edges of the beam, so as to clasp it. A bolt, d, may pass through these flanges and the web of the beam, to secure the plate firmly, and the spaces between the flanges and the beam may afterward be filled with 85 lead cement or any substance which will form a solid joint.

Having thus described my invention, what I claim as new, and desire to secure by Letters Patent, is—

1. In combination with girder A A and abutting beam B, the independent wrought-iron plates extending across the girder and above and below the beam, and a clamp, as means for securing the end of the abutting beam and the plates together, substantially as herein described.

2. The girder A A and abutting beam B, in

combination with the plates C and flanges to secure them to the end of the abutting beam, substantially as herein described.

3. The girder A, A and abutting beam B, in combination with the plates C, extending across the girder and upon the end of the beam above and below, with means for securing and clamping said plates, and check-pieces fitting be-

tween the end of the beam and the bolts or clamp, substantially as herein described. 10

In witness whereof I have hereunto set my hand.

PETER H. JACKSON.
